(57) **ABSTRACT**

Disclosed is a developing cartridge configured to be removably mounted in a main assembly of an imaging apparatus. In some embodiments disclosed, the developing cartridge includes: a cartridge body; a drive force receiving unit including a coupling member, disposed at a first end of the developing cartridge, configured to receive a drive force from the imaging apparatus; a driving member, disposed at the first end of the developing cartridge, configured to receive the drive force and move; a transmission member, receiving a force from the driving member to cause at least a portion of the transmission member to move along a longitudinal direction of the cartridge body; and a detected member provided at a second end of the developing cartridge, configured to be driven by the transmission member.

DEVELOPING CARTRIDGE

CROSS-REFERENCE TO RELATED
APPLICATIONS

This application is a continuation-in-part of International Application No. PCT/CN2023/082426, filed on Mar. 20, 2023, which claims priority to Chinese Patent Application No. 202220604017.8, filed on Mar. 20, 2022, Chinese Patent Application No. 202210716526.4, filed on Jun. 22, 2022, and Chinese Patent Application No. 202221938084.X, filed on Jul. 25, 2022. All of the aforementioned patent applications are hereby incorporated by reference in their entireties.

TECHNICAL FIELD

15

The present disclosure relates to the field of electrophotographic imaging apparatus, and in particular to a developing cartridge.

BACKGROUND

As is known, as an electrophotographic type imaging apparatus, such an imaging apparatus includes a main assembly, a photoconductor drum provided in the main assembly, and a developing cartridge for supplying developer to the photoconductor drum.

Such an imaging apparatus includes a detection unit for judging information about a developing cartridge installed in the imaging apparatus. For example, the detection unit is configured to determine whether a newly installed developing cartridge in the imaging apparatus is a new product, or the size and capacity information of the developing cartridge, etc.

In this type of imaging apparatus, a developing cartridge can be mounted in a removable manner to a main assembly of the imaging apparatus, and the main assembly is provided with a transmission mechanism and a light sensor. The developing cartridge rotatably supports a detected mechanism, and the detected mechanism is provided with a protruding portion (detected member) that can contact and push the transmission mechanism. When the developing cartridge is mounted to the main assembly, the detected mechanism is driven to rotate and the protruding part pivots the transmission mechanism. The optical sensor detects the pivoting motion of the transmission mechanism, and the imaging apparatus determines the information of the developing cartridge based on the detection result of the optical sensor.

Similarly, in addition to judging the information of the developing cartridge by the detection result of the light sensor, there is also a way of detecting the information of the developing cartridge by means of capacitance, and the way of detecting the capacitance may be that the pivoting motion of the protruding portion contacting the transmission mechanism causes the capacitance to change, and the information of the developing cartridge is thus judged accordingly. Another way is to judge the information of the developing cartridge by the change of voltage or current of the circuit by switching on and off, and specifically, the switch can be disconnected or connected by the pivoting motion of the protruding part contacting the transmission mechanism.

There exists a developing cartridge in which a drive force receiving unit is provided at a first end along a longitudinal direction, a detected member is provided at a second end opposite to the first end, and a rotary shaft configured to receive a rotational drive force and rotate is provided between the first end and the second end so as to be

2

configured to transmit a rotational drive force of the drive force receiving unit from the first end to the second end of the developing cartridge, thereby driving the detected member provided at the second end. In this case, a stirring member is rotatably provided in the developing cartridge for stirring the developer, and the rotational shaft of the stirring member is configured to transmit the rotational drive force for driving the detected member, which results in the rotational shaft of the stirring member being subjected to the force of stirring the developer and driving the detected member at the same time, and there is a risk of deformation or even fracture.

SUMMARY

15

The main object of the present disclosure is to provide a new driven structure of the detected member, wherein there is no need to transmit a force to drive the detected member through the rotational shaft of the stirring member, in order to eliminate the risk that the rotational shaft of the stirring member is susceptible to deformation or even fracture.

The object of the present disclosure can be achieved by the following technical solutions.

According to one aspect of the present disclosure, a developing cartridge removably mountable in a main assembly of an imaging apparatus along a front-rear direction of the developing cartridge comprises: a cartridge body; a drive force receiving unit, provided at a first end of the developing cartridge; a driving member, provided at the first end of the developing cartridge and configured to receive a drive force and move; a transmission member configured to receive a force from the driving member, wherein the force from the driving member causes at least a portion of the transmission member to move in a longitudinal direction of the cartridge body; a detected member, provided at a second end of the developing cartridge opposite to the first end along the longitudinal direction of the cartridge body, the detected member being configured to be driven by the transmission member; and a sliding groove portion provided on an upper surface of the cartridge body, wherein the transmission member is at least partially mounted in the sliding groove portion, and the sliding groove portion is configured to restrict movement of the transmission member along an up-down direction perpendicular to the longitudinal direction and a front-rear direction of the cartridge body.

In some embodiments, the sliding groove portion protrudes from the upper surface of the cartridge body, and the sliding groove portion is positioned higher than the transmission member along the up-down direction.

In some embodiments, a plurality of sliding groove portions are provided and are spaced apart along the longitudinal direction of the cartridge body.

In some embodiments, the detected member is configured as a sliding member and is configured to slide in response to a pushing force from the transmission member.

In some embodiments, the detected member is configured to move linearly in the front-rear direction of the cartridge body.

In some embodiments, the transmission member comprises a rod portion slidably disposed on the cartridge body and extending along the longitudinal direction, and at least a portion of the rod portion is disposed between the first end and the second end of the developing cartridge.

In some embodiments, the detected member comprises a force receiving portion and a detected portion, the force receiving portion being movably connected to the rod por-

tion, and the detected portion extending in a direction different from an extension direction of the force receiving portion.

In some embodiments, the driving member comprises a cam member, the cam member comprises a main body portion and a cam portion configured to push the transmission member, and the cam portion protrudes from an end face of the main body portion along the longitudinal direction of the cartridge body.

In some embodiments, the developing cartridge further comprises a clutch mechanism configured to interrupt transmission of the drive force to the transmission member, wherein the clutch mechanism comprises a missing tooth portion provided on an outer circumferential surface of the main body portion.

In some embodiments, the developing cartridge further comprises a clutch mechanism configured to interrupt transmission of the drive force to the transmission member, wherein the clutch mechanism comprises a notched portion provided on a radially outer side of the main body portion.

In some embodiments, the transmission member comprises a force receiving portion configured to be pushed by the cam portion, and the force receiving portion is configured to fall into the notched portion such that the force receiving portion no longer receives a force from the cam portion.

In some embodiments, the transmission member is movable between a first position not pushed by the cam portion and a second position pushed by the cam portion.

In some embodiments, the developing cartridge further comprises a resilient member configured to apply a force to the transmission member to enable the transmission member to move from the second position towards the first position.

In some embodiments, the developing cartridge further comprises a resilient member provided at a first end of the rod portion and configured to support the rod portion.

In some embodiments, the developing cartridge further comprises a resilient member, wherein one end of the resilient member resists the cartridge body and another end of the resilient member resists the transmission member, and the transmission member comprises a housing portion for housing the resilient member.

According to another aspect of the present disclosure, a developing cartridge removably mountable in a main assembly of an imaging apparatus along a front-rear direction of the developing cartridge comprises: a cartridge body; a drive force receiving unit, provided at a first end of the developing cartridge; a driving member, provided at the first end of the developing cartridge and configured to receive a drive force and move; a transmission member configured to receive a force from the driving member, wherein the force from the driving member causes at least a portion of the transmission member to move in a longitudinal direction of the cartridge body; a detected member, provided at a second end of the developing cartridge opposite to the first end along the longitudinal direction of the cartridge body, the detected member being configured to be driven by the transmission member; and a sliding groove portion provided on an upper side of the cartridge body, wherein the transmission member is at least partially and slidably accommodated in the sliding groove portion, and an upper surface of the transmission member is flush with or lower than an upper surface of the cartridge body.

In some embodiments, the developing cartridge further comprises a covering portion at least partially covering the transmission member.

In some embodiments, opposite ends of the covering portion are provided with a first exposed portion and a second exposed portion, respectively, the first exposed portion and the second exposed portion are configured as openings; one end of the transmission member is configured to extend through the first exposed portion; and a detected portion of the detected member is configured to be exposed through the second exposed portion.

In some embodiments, a second end of the covering portion is provided with an accommodating cavity for accommodating the detected member.

In some embodiments, the transmission member is a flexible transmission member, and the driving member and the flexible transmission member form a transmission direction-change unit configured to transmit a rotational force of the drive force receiving unit to the detected member to cause the detected member to move, a movement direction of the detected member intersects with a rotational axis of the drive force receiving unit, and the movement of the detected member is a linear motion, a rotational motion, or a curvilinear motion.

According to still another aspect of the present disclosure, a developing cartridge removably mountable in a main assembly of an imaging apparatus comprises: a cartridge body; a drive force receiving unit comprising a coupling member, provided at a first end of the developing cartridge and configured to receive a drive force from the imaging apparatus; a driving member, provided at the first end of the developing cartridge and configured to receive the drive force and move; a transmission member configured to receive a force from the driving member, wherein the force causes at least a portion of the transmission member to move in a longitudinal direction of the cartridge body; and a detected member, provided at a second end of the developing cartridge and configured to be driven by the transmission member.

In some embodiments, the detected member is configured as a sliding member, and is configured to slide in response to a pushing force from the transmission member.

In some embodiments, the drive force receiving unit further comprises a stirring member gear, and the driving member is configured to engage with the stirring member gear.

In some embodiments, the driving member comprises a cam member, the cam member including a main body portion and a cam portion configured to push the transmission member, and wherein the cam portion protrudes from an end face of the main body portion along the longitudinal direction of the cartridge body.

In some embodiments, the cartridge body is provided with a sliding groove portion, and at least a portion of the transmission member is disposed in the sliding groove portion.

In some embodiments, the sliding groove portion protrudes from an outer surface of the cartridge body and is positioned higher than the transmission member, and wherein a side of the sliding groove portion facing the transmission member is configured to contact an outer surface of the transmission member, thereby restricting movement of the transmission member along an up-down direction of the developing cartridge.

In some embodiments, the sliding groove portion is provided on an upper side of the cartridge body, the transmission member is slidably accommodated in the sliding groove portion, and an upper surface of the transmission member is flush with or lower than an upper surface of the cartridge body.

In some embodiments, two sliding groove portions are provided on opposite sides of the transmission member; or multiple sliding groove portions are spaced apart along the longitudinal direction of the cartridge body.

In some embodiments, the detected member is configured to move in a front-rear direction of the developing cartridge.

In some embodiments, the developing cartridge further comprises a rotating body configured to receive the drive force transmitted by the coupling member and rotate, wherein the detected member is configured to rotate or pivot with the rotation of the rotating body.

In some embodiments, the driving member comprises a first transmission body, a rotational axis of the first transmission body being perpendicular to a rotational axis of the coupling member, wherein the first transmission body is provided with a first rotational force receiving portion for receiving rotational force, the first rotational force receiving portion comprising a gear portion.

In some embodiments, the transmission member comprises a flexible transmission member, the flexible transmission member connecting the first transmission body and the rotating body; wherein rotation of the first transmission body is configured to drive the flexible transmission member to rotate and move along the longitudinal direction of the cartridge body, thereby causing the rotating body to rotate through the flexible transmission member.

In some embodiments, the driving member comprises a first transmission body and a second transmission body, wherein the second transmission body is configured to receive a drive force from the drive force receiving unit, the first transmission body receiving the drive force from the second transmission body; wherein both the first transmission body and the second transmission body comprise bevel gear structures.

In some embodiments, the detected member is provided on the rotating body and is configured to rotate with the rotating body.

In some embodiments, the driving member comprises a first transmission body and a flexible transmission member; wherein one end of the flexible transmission member is wound on or connected to the first transmission body, and the other end is wound on the rotating body, with the winding directions of the flexible transmission member on the first transmission body and the rotating body being opposite to each other.

In some embodiments, the detected member is provided on and protrudes from an outer surface of the flexible transmission member.

In some embodiments, the transmission member comprises a flexible transmission member configured to operatively connect the driving member and the rotating body, thereby causing the rotating body to rotate; wherein the driving member comprises a first transmission body and a second transmission body, the first transmission body being provided with a first rotational force receiving portion for receiving rotational force and a first mounting portion for mounting the flexible transmission member, the second transmission body being provided with a second rotational force receiving portion and a rotational force transmitting portion, wherein the second rotational force receiving portion is configured to receive rotational drive force from the drive force receiving unit, and the rotational force transmitting portion is connected to the first rotational force receiving portion to transmit rotational drive force to the first transmission body.

In some embodiments, the first rotational force receiving portion comprises a first gear portion, the first mounting

portion comprises an annular groove provided on a shaft portion of the first transmission body, the annular groove rotating with the rotation of the first gear portion; wherein the second rotational force receiving portion comprises a second gear portion, and the rotational force transmitting portion comprises a screw rod portion that meshes with the first gear portion for transmission.

In some embodiments, the developing cartridge further comprises a direction changing member, wherein the flexible transmission member is supported by the direction changing member to change direction by bending downward from an upper side.

In some embodiments, the developing cartridge further comprises a transmission interruption mechanism configured to interrupt the drive force transmitted from the first transmission body to the detected member, thereby causing the detected member to stop moving; wherein the transmission interruption mechanism comprises a smooth surface provided on an inner side of the flexible transmission member, such that when the smooth surface moves to a position in contact with the first transmission body, the flexible transmission member stops rotating.

In some embodiments, the driving member comprises a main body portion, a gear portion configured to engage with the drive force receiving unit, and an action portion configured to push the transmission member; wherein the transmission member is movable between a first position not pushed by the action portion and a second position pushed by the action portion.

In some embodiments, the action portion extends along an axial direction or a radial direction with respect to a rotational axis of the driving member.

In some embodiments, a rotational axis of the driving member is either perpendicular or parallel to a rotational axis of the coupling member.

In some embodiments, the transmission member is a sliding member comprising: a force receiving portion; and a rod portion slidably disposed on the cartridge body; wherein the action portion is configured to push the force receiving portion, causing the sliding member to slide along the longitudinal direction of the cartridge body.

In some embodiments, the transmission member is a pivoting member comprising: a force receiving portion; and a rod portion pivotally disposed on the cartridge body; wherein the action portion is configured to push the force receiving portion, causing the pivoting member to pivot in either a front-rear direction or an up-down direction of the cartridge body, resulting in at least a portion of the pivoting member moving along the longitudinal direction of the cartridge body.

In some embodiments, the developing cartridge further comprises a clutch mechanism configured to selectively interrupt transmission of the drive force to the transmission member.

In some embodiments, the clutch mechanism comprises a notched portion provided on an outer side of the main body portion, and wherein the action portion is configured to engage with the notched portion to interrupt the transmission of the drive force.

In some embodiments, the clutch mechanism comprises: a forcing structure configured to move at least a portion of the driving member, thereby interrupting the transmission of the drive force; and a retracting structure configured to provide a displacement space for the movement of the at least a portion of the driving member.

In some embodiments, the driving member and the drive force receiving unit form a geared engagement, and wherein

the clutch mechanism comprises a missing tooth portion provided on the driving member.

In some embodiments, the detected member is pivotally connected, fixedly connected, or integrally molded with the transmission member.

In some embodiments, the drive force receiving unit further comprises one or more of a development roller gear, a stirring member gear, a powder feed roller gear, and an idler wheel. The driving member can engage with one of the development roller gear, stirring member gear, powder feed roller gear, and idler wheel, for example, engaging with the stirring member gear. The cartridge body is provided with a first side wall and a second side wall along its length, and at least a portion of the transmission member is disposed between the first side wall and the second side wall.

In some embodiments, the driving member is a cam member, the action portion is a cam portion, and the developing cartridge further comprises a resilient member, the resilient member being configured to apply a force to the transmission member to enable the transmission member to move in a direction from the second position to the first position.

In some embodiments, the cam member has a first bevel gear teeth portion and the drive force receiving unit has a second bevel gear teeth portion engaged with the first bevel gear teeth portion.

In some embodiments, the driving member is a grooved cam wheel member, the grooved cam wheel member comprising a guiding groove, the action portion being provided within the guiding groove or forming part of the guiding groove.

In some embodiments, the developing cartridge further comprises a rotating body, the rotating body having a rotational axis which intersects with the rotational axis of the coupling member; the driving member comprises a first transmission body having a rotational axis perpendicular to the rotational axis of the coupling member, the first transmission body being provided with a first rotational force receiving portion and a first mounting portion; the transmission member is a flexible transmission member, the flexible transmission member connecting the first mounting portion and the rotating body to rotate the rotating body, the detected member moving with the rotating body or the flexible transmission member to be detectable by a detection unit.

In some embodiments, the driving member further comprises a second transmission body, the second transmission body being provided with a second rotational force receiving portion and a rotational force transmitting portion whose rotational axis intersects with the rotational axis of the first rotational force receiving portion; wherein the second rotational force receiving portion engages with the drive force receiving unit to receive a rotational drive force, and the first rotational force receiving portion engages with the rotational force transmitting portion.

In some embodiments, the second rotational force receiving portion is a gear portion, one of the first rotational force receiving portion and the rotational force transmitting portion is a screw portion, and the other is a gear portion. Alternatively, both the first rotational force receiving portion and the rotational force transmitting portion are bevel gear teeth portions.

In some embodiments, the detected member is provided on an outer surface of the flexible transmission member or on an outer surface of the rotating body.

In some embodiments, the flexible transmission member is a flexible belt or chain, with one end of the flexible belt

or chain being fitted to the shaft of the first transmission body and the other end being fitted to the shaft of the rotating body.

In some embodiments, the detected member is provided on an outer surface of the flexible belt or chain, or on an outer surface of the rotating body.

In some embodiments, the flexible transmission member is a flexible cord or wire, with one end of the flexible cord or wire being connected to a shaft portion of the first transmission member and the other end being wrapped around a shaft portion of the rotating body. The detected member is provided on an outer surface of the rotating body.

In some embodiments, an upper side of the cartridge body is further provided with an accommodating groove, at least a portion of the transmission member being provided in the accommodating groove.

In some embodiments, the developing cartridge further comprises a covering portion covering at least a portion of the transmission member.

In a developing cartridge having the above structure, the detected member is driven by a transmission member which is set to drive the detected member by moving at least a portion thereof along a longitudinal direction of the cartridge body, and there is no need to transmit a force to drive the detected member through a rotary axis of the stirring member, so that not only the risk of deformation or even fracture of the rotary axis of the stirring member is eliminated, but also the flexibility in design of the developing cartridge can be improved and the detection accuracy can be ensured.

BRIEF DESCRIPTION OF THE DRAWINGS

DETAILED DESCRIPTION OF THE EMBODIMENTS

Embodiments disclose a developing cartridge of an imaging apparatus, the imaging apparatus comprises a main assembly and a detection unit 100 (see FIG. 1), a photoconductor drum, and a drive transmission member disposed in the main assembly, the detection unit 100 and the drive transmission member are disposed on different sides of the main assembly. The detection unit 100 is provided on one side of the main assembly for detecting information of a developing cartridge mounted in the main assembly, and is provided with a transmission mechanism 200 (see FIG. 1), which can receive a force of the developing cartridge and pivot, and the imaging apparatus determines the information of the developing cartridge by the situation in which the pivoting motion of the transmission mechanism 200 obscures the sensor 300 (see FIG. 1). The drive transmission member is provided on the other side of the main assembly

11

for transmitting a drive force to the developing cartridge. The structure and detection principle of the imaging apparatus can be referred to the structure and detection principle of the printer disclosed in Chinese Patent Publication No. CN105759586A, and relevant prior art will not be repeated herein.

Hereinafter, the structure of the developing cartridge will be described in detail in connection with the embodiments.

Embodiment 1

As shown in FIGS. 1 to 3, the developing cartridge 10a is removably mountable in the main assembly of the above-described imaging apparatus. The specific structure of which includes cartridge body 1a and drive force receiving unit 2a.

The cartridge body 1a is substantially cuboid in shape and is provided with a first side wall 11a and a second side wall 12a along the longitudinal direction L thereof. It generally includes a powder compartment 13a for accommodating developer, a development roller 14a, a powder feed roller, and a stirring member 15a. The development roller 14a is disposed on the front side of the developing cartridge 10a in the direction in which the developing cartridge 10a is mounted in the imaging apparatus, and is exposed from the front side of the cartridge body 1a and opposed to the photoconductor drum when the developing cartridge 10a is mounted in the imaging apparatus, to enable development work to be carried out. The powder feed roller faces the development roller 14a and is configured to deliver developer to the development roller 14a; and the stirring member 15a is configured to stir the developer accommodated in the powder compartment 13a.

The drive force receiving unit 2a is provided at a first side (or a first end of the developing cartridge 10a) along the longitudinal direction L of the cartridge body 1a. It is configured to receive a drive force from a drive transmission member of the imaging apparatus and transmit a rotational drive force to rotational members such as the development roller 14a. The drive force receiving unit 2a disclosed herein may include a coupling member 21a, or may include a coupling member 21a and one or more of a development roller gear 22a, a powder feed roller gear 23a, a stirring member gear, and an idler wheel 24a. In this embodiment, the drive force receiving unit 2a includes the coupling member 21a, the development roller gear 22a, the powder feed roller gear 23a, and the idler wheel 24a.

The coupling member 21a is rotatably supported on the first side wall 11a of the cartridge body 1a, and its rotational axis extends along the longitudinal direction L of the developing cartridge 10a parallel to the rotational axis of the development roller 14a. The coupling member 21a is provided with a drive force receiving portion 211a and a first gear portion 212a. The drive force receiving portion 211a is coupled with the drive transmission member of the imaging apparatus and receives the drive force. The first gear portion 212a is configured to engage with the development roller gear 22a, the powder feed roller gear 23a, and the idler wheel 24a to transmit a rotary drive force to the development roller gear 22a, the powder feed roller gear 23a, and the idler 24a. The development roller gear 22a and the powder feed roller gear 23a are provided at the ends of the development roller 14a and the powder feed roller, respectively, to rotate the development roller 14a and the powder feed roller. The stirring member gear is provided at an end portion of the stirring member 15a and meshes with the idler wheel 24a to drive the stirring member 15a to rotate.

12

The developing cartridge 10a is provided with a first end cap 101a and a second end cap 102a at each end of the developing cartridge 10a, the first end cap 101a being disposed on the outer side of the first side wall 11a to protect the drive force receiving unit 2a. The second end cap 102a is disposed on the outer side of the second side wall 12a, from which the detected member 6a (which will be described in more detail later) can be exposed.

As shown in FIGS. 4 to 6, in this embodiment, the developing cartridge 10a is further provided with a driving member 3a, a transmission member 4a, a resilient member 5a, and a detected member 6a.

For ease of description, a direction parallel to a mounting direction P of the developing cartridge 10a is taken as a front-rear direction of the developing cartridge 10a, a position where the development roller 14a is located is taken as a front side of the developing cartridge 10a, and a side opposite to the front side is taken as a back side; a longitudinal direction L of the cartridge body 1a is taken as a right-left direction of the developing cartridge 10a, with a first side wall 11a located on the left side of the developing cartridge 10a and a second side wall 12a located on the right side; the direction perpendicular to the front-rear direction and the left-right direction is the up-down direction T. When the developing cartridge is mounted in the imaging apparatus, the upper side of the developing cartridge is above and the lower side is below.

The driving member 3a is configured to receive a drive force and move. The drive force reception may be direct from the drive force receiving unit 2a or indirect. The drive force may be in the form of a rotational drive force or a pushing force, and the corresponding movement of the driving member 3a may be rotation or sliding.

Preferably, the driving member is provided in a rotatable manner. The driving member may include a main body portion, a second gear portion configured to engage with the drive force receiving unit, and an action portion configured to push the transmission member. The action portion may extend in the direction of the rotational axis of the driving member or in the radial direction.

In this embodiment, the driving member is a cam member 3a, and the action portion is a cam portion. Specifically, the cam member 3a includes a cylindrical main body portion 31a, and the main body portion 31a is provided with a second gear portion 32a configured to engage with the drive force receiving unit 2a and a cam portion configured to push the transmission member 4a. In the present disclosure, the cam portion may be or include a protruding portion extending in the direction of the rotational axis of the cam member or in the radial direction.

In this embodiment, the rotational axis of the cam member 3a is parallel to the longitudinal direction L of the cartridge body 1a, and the cam portion includes two cam portions; a first cam portion 33a and a second cam portion 34a, and the first cam portion 33a and the second cam portion 34a have essentially the same shape and structure, and the first cam portion 33a will be described as an example below.

The first cam portion 33a protrudes from the end face of the main body portion 31a along the longitudinal direction L of the cartridge body 1a. Specifically, this first cam portion 33a protrudes along the longitudinal direction L of the cartridge body 1a in a direction away from the first side wall 11a, and it is also provided with a first guiding surface 35a and a second guiding surface 36a on its side, and in the rotational direction of the cam member 3a, the first guiding surface 35a is located upstream of the second guiding surface 36a. The main body portion 31a is cylindrical in

13

shape, and the two cam portions are provided on the circumference of the main body portion **31a** at predetermined spaced intervals.

In this embodiment, the cam member **3a** is provided at an end portion of the stirring member **15a**, which can serve as a gear for the stirring member **15a**, and the second gear portion **32a** engages with the idler wheel **24a** of the drive force receiving unit **2a** to receive a rotational drive force which is configured to drive the stirring member **15a** to rotate.

Optionally, the cam member **3a** may also be provided at the end of the development roller **14a** or the powder feed roller, or may be independently provided on the cartridge body **1a**.

The transmission member **4a** is configured to receive a force from the driving member **3a** to cause at least a portion of the transmission member **4a** to move along the longitudinal direction **L** of the cartridge body **1a**. The transmission member **4a** is configured to drive the detected member **6a**. This driving can be achieved in various ways: the detected member **6a** may be fixedly connected to the transmission member **4a** or integrally molded it and move along with the movement of the transmission member **4a**; the detected member **6a** may be movably connected to the transmission member **4a**; or the driving can be achieved by the transmission member **4a** contacting the detected member **6a**.

The transmission member **4a** is movable between a first position not pushed by the cam portion and a second position pushed by the cam portion. The transmission member **4a** is provided with a force receiving portion **41a** that receives a force from the cam portion of the cam member **3a**, and the force receiving portion **41a** is also configured to be pushed by the cam portion so as to enable the transmission member **4a** to move between the first position and the second position.

In this embodiment, the transmission member **4a** is a sliding member comprising a force receiving portion **41a** and a rod portion **42a**. The rod portion **42a** extends along the longitudinal direction **L** of the cartridge body **1a**, with at least a portion of it disposed between the first side wall **11a** and the second side wall **12a**. The rod portion **42a** is slidably disposed on the cartridge body **1a**, and the cam portion is configured to push the force receiving portion **41a** to slide along the longitudinal direction **L** of the cartridge body **1a**.

The cartridge body **1a** is provided with a sliding groove portion **16a** as an example of an accommodating groove for the transmission member, and the transmission member **4a** is at least partially mounted in the sliding groove portion **16a** to enable it to slide along the longitudinal direction **L** of the cartridge body **1a**. The number of sliding groove portions **16a** may be one or more. The manner of realizing the sliding of the transmission member **4a** is not limited to the slide groove method, but may also include the provision of a storage portion for storing the transmission member **4a**, or other methods.

As shown in FIGS. 4 and 5, the sliding groove portion **16a** protrudes from an outer surface of the cartridge body **1a** and is positioned higher than the transmission member **4a**. A side of the sliding groove portion **16a** facing the transmission member **4a** is configured to contact an outer surface of the transmission member **4a**, thereby restricting movement of the transmission member **4a** along an up-down direction **T** of the developing cartridge.

As an example, there may be two sliding groove portions **16a**, and the two sliding groove portions **16a** are provided on opposite sides of the transmission member **4a**. Alternatively, there may be multiple sliding groove portions **16a**, and the

14

multiple sliding groove portions **16a** are spaced apart along the longitudinal direction **L** of the cartridge body **1a**.

The resilient member **5a** is configured to apply a force to the transmission member **4a** to enable it to move from the second position towards the first position.

Specifically, the resilient member **5a** is a compression spring, one end of which resists the resilient member support **51a** on the cartridge body **1a**, and the other end of which resists a portion of the transmission member **4a**. When the transmission member **4a** moves from the first position to the second position, it compresses the resilient member **5a** to the left. More specifically, the transmission member **4a** has a housing portion in which the resilient member **5a** is housed.

Optionally, such a resilient member **5a** may also be an extension spring, a torsion spring, or an elastic sponge body, etc.

The detected member **6a** is provided at the second end of the developing cartridge **10a** and is configured to be driven by the transmission member **4a**. This driving may be either direct or indirect. For example, the detected member **6a** may be integrally molded with the transmission member **4a**, connected in a linkage relationship, or driven at a predetermined distance apart etc. All of these fall within the scope of driving in the disclosure.

In this embodiment, the detected member **6a** is pivotally disposed at the second end of the cartridge body **1a** and is configured to be driven by the transmission member **4a**. Specifically, the detected member **6a** is provided with a force receiving portion **61a**, a connection portion **62a**, and a detected portion **63a**, and the connection portion **62a** is pivotally connected to a pivot axis on the cartridge body **1a** or the second end cap **102a** forming a pivoting center.

The force receiving portion **61a** extends from the connection portion **62a** and is connected to one end of the transmission member **4a** in a pivotal manner (e.g., to form a link mechanism). Specifically, the end portion of the rod portion **42a** is provided with a circular hole and is movably connected to the shaft portion (force receiving portion **61a**) of the detected member **6a**, so that when the transmission member **4a** moves along the longitudinal direction **L** of the cartridge body **1a**, it can drive the detected member **6a** to pivot. The detected portion **63a** extends along a direction different from the extension direction of the force receiving portion **61a**, so as to be able to trigger the detection unit **100** of the imaging apparatus when the detected member **6a** pivots.

It can be understood that in this embodiment, during the pivoting movement of the detected member **6a**, the detected member **6a** can also be considered to move along a front-rear direction of the cartridge body **1a**. In addition, this embodiment does not limit the specific manner in which the detected member **6a** moves along the front-rear direction of the cartridge body **1a**. For example, it could also move in a linear translation or along an arc-shaped path, which is not limited herein.

In this embodiment, the developing cartridge **10a** further comprises a clutch mechanism **7a** for interrupting the transmission of the drive force to the transmission member **4a**. Specifically, the clutch mechanism **7a** includes a notched portion **71a** provided on the cam member **3a**. The notched portion **71a** is provided on the radially outer side of the main body portion **31a** of the cam member **3a**, and the force receiving portion **41a** of the transmission member **4a** can fall into the notched portion **71a**. When this happens, the force receiving portion **41a** is detached from the path through which the rotational process of the cam portion

15

passes, no longer receives a force from the cam portion, thus interrupting the drive force transmission.

The process by which the developing cartridge 10a is detected by the detection unit 100 of the imaging apparatus will now be described with reference to FIGS. 4 to 7.

As shown in FIG. 6, in this embodiment, when the developing cartridge 10a is in an unused state, the transmission member 4a is in the second position (initial position), the resilient member 5a is in a compressed state, and the detected member 6a is in a state where it has not triggered the detection unit 100.

The user installs the developing cartridge 10a into the imaging apparatus, and the coupling member 21a is coupled to a drive transmission member of the imaging apparatus. When the imaging apparatus begins to operate, the idler wheel 24a receives the drive force from the coupling member 21a and rotates the cam member 3a. As the cam member 3a rotates, the force receiving portion 41a moves from the top of the first cam portion 33a along the first guiding surface 35a towards the root of the first cam portion 33a under the pushing of the first cam portion 33a. At this time, under the action of the elastic restoring force of the resilient member 5a, the transmission member 4a slides to the right side, and the detected member 6a rotates and contacts the detection unit 100 of the imaging apparatus, driven by the transmission member 4a.

As the cam member 3a continues to rotate, the force receiving portion 41a of the transmission member 4a moves from the root of the cam portion to the top of the second cam portion 34a along the second guiding surface 36a of the second cam portion 34a under the pushing of the second cam portion 34a, at which time the transmission member 4a slides to the left and rotates the detected member 6a, which disengages from the detection unit 100. As the force receiving portion 41a moves along the first guide surface 35a from the top of the second cam portion 34a to the root of the second cam portion 34a, under the action of the elastic restoring force of the resilient member 5a, the transmission member 4a slides to the right and rotates the detected member 6a, causing the detected member 6a to contact the detection unit 100 for a second time. As the cam member 3a continues to rotate, the force receiving portion 41a moves along the end face of the cam member 3a and ultimately falls into the notched portion 71a as shown in FIG. 7. The cam member 3a continues to rotate but the transmission member 4a is no longer pushed, and the detection is completed.

The number of cam portions can be set according to the number of times the detection unit 100 needs to be toggled, for example, one cam portion can be set when it needs to be toggled once, and multiple cam portions can be set when it needs to be toggled multiple times. The structures of different cam portions can also be different, and they can be set according to the strength and amplitude of the pushing force on the transmission member, so as to differentiate between different types or capacities of developing cartridges.

In the developing cartridge 10a with the above-described structure, the transmission member 4a moves at least partially along the longitudinal direction L of the cartridge body 1a. As can be seen with reference to FIG. 7, the transmission member 4a moves along the longitudinal direction L of the cartridge body 1a by a distance d1, which is the same as or greater than the protruding amount (i.e., the distance from the root of the cam portion to the top of the cam portion) of the cam portion.

The developing cartridge 10a with the above-described structure eliminates the need to transmit the drive force for driving the detected member 6a through the rotary shaft of

16

the stirring member 15a, thereby eliminating the risk of deformation or even fracture of the rotary shaft of the stirring member 15a. The adoption of a sliding method to achieve the transmission of the drive force from the first end 5 of the developing cartridge 10a to the second end of the developing cartridge 10a solves the problem of delayed transmission of the drive force caused by the deformation of the rotary shaft of the stirring member 15a, and improves the detection accuracy. Additionally, the torque required for the developing cartridge 10a is greatly reduced, resulting in more stable operation of the developing cartridge 10a.

In some embodiments, the detected member is integrally molded with the transmission member 4a, and the detected member is provided at the end of the transmission member 4a and moves with the movement of the transmission member 4a so as to be configured to trigger the detection unit 100 of the imaging apparatus.

In some embodiments, the detected member 6a is set up as a sliding member, relying on the pushing force of the transmission member 4a for sliding.

In some embodiments, the resilient member 5a is not connected to the transmission member 4a, but is set to be connected to the detected member 6a, which pushes the transmission member 4a to move from the second position towards the first position.

In some embodiments, the detected member does not come into contact with the transmission member, i.e., the two can be spaced apart by a predetermined distance, as long as the detected member 6a can be driven when the transmission member 4a moves.

In some embodiments, the clutch mechanism may also be provided between the drive force receiving unit 2a and the cam member 3a to indirectly interrupt transmission of the drive force to the transmission member 4a by interrupting the transmission of the drive force between the drive force receiving unit 2a and the cam member 3a.

In some embodiments, the driving member 3a is a rack structure engaged with the drive force receiving unit 2a, which receives the drive force to move and is configured to 40 push the transmission member 4a along the longitudinal direction of the developing cartridge.

In some embodiments, the initial position of the transmission member 4a is the first position, and the transmission member 4a drives the detected member 6a to contact the detection unit in the imaging apparatus when it moves from the first position to the second position.

In some embodiments, the detected member 6a may or may not be in contact with the transmission mechanism 200 of the detection unit 100 in an initial position.

In some embodiments, the above variations are combined according to design needs.

Embodiment 2

55 This embodiment is an improvement based on Embodiment 1 and its variations, the shape and structure of the developing cartridge in Embodiment 2 are essentially the same as the developing cartridge in Embodiment 1, the same parts will not be repeated, and the following mainly introduces the differences.

As shown in FIGS. 8 and 9, in the present embodiment, the cam portion protrudes in a direction opposite to the direction of protrusion of the cam portion in Embodiment 1. In this embodiment, there are two cam portions: a first cam portion 33b and a second cam portion 34b. The first cam portion 33b will be described as an example below. The first cam portion 33b protrudes from the end face of the main

body portion 31b in a direction towards the first side wall 11b and is configured to push the force receiving portion 41b of the transmission member 4b.

The direction of force applied by the resilient member 5b to the transmission member 4b is towards the leftward direction, and the resilient member support portion 51b is located on the right side of the resilient member 5b. The initial position of the transmission member 4b is in the first position where the force receiving portion 41b of the transmission member 4b abuts against the right side end face of the main body portion 31b.

In this embodiment, the detected member 6b is configured to pivot in the up-down direction along the cartridge body, specifically the detected member 6b is provided with a force receiving portion 61b, a connection portion 62b, and a detected portion 63b, the connection portion 62b is pivotally connected to the second end cap 102b, the force receiving portion 61b extends from the connection portion 62b towards the transmission member 4b. The force receiving portion 61b is also provided with a pressing surface 611b, which, when pressed by the transmission member 4b, causes the detected member 6b to rotate around the pivoting center. The detected portion 63b is provided on the other side of the connection portion 62b, and when the pressing surface 611b is pushed by the transmission member 4b, the detected portion 63b tilts upwardly to be able to trigger the detection unit 100 of the imaging apparatus.

Optionally, the moving direction of the detected portion 63b may be set according to its position relative to the detection unit 100 of the imaging apparatus.

The process by which the developing cartridge 10b is detected by the detection unit 100 of the imaging apparatus will now be described with reference to FIGS. 8 and 9.

As shown in FIG. 8, in this embodiment, when the developing cartridge 10b is in an unused state, the transmission member 4b is in the first position (initial position), the resilient member 5b is not compressed, and the detected member 6b has not triggered the detection unit 100.

When the imaging apparatus begins to operate, the cam member 3b receives a drive force through the second gear portion 32b and rotates, causing the force receiving portion 41b to move from the root portion of the first cam portion 33b along the second guiding surface 36b towards the top portion of the first cam portion 33b under the pushing of the first cam portion 33b. At this time, the transmission member 4b is forced to slide to the right. As shown in FIG. 9, the transmission member 4b is in the second position, the resilient member 5b is compressed, the transmission member 4b presses against the pressing surface 611b of the detected member 6b causing the detected member 6b to rotate, and the detected portion 63b tilts upwardly to contact the detection unit 100 of the imaging apparatus.

As the force receiving portion 41b moves from the top of the first cam portion 33b along the first guiding surface 35b towards the root of the first cam portion 33b, the transmission member 4b is forced to move to the left under the action of the resilient restoring force of the resilient member 5b, the transmission member 4b no longer presses the detected member 6b, and the detected portion 63b of the detected member 6b can move downwardly under its own gravity and return to its initial state. When the second cam portion 34b pushes the force receiving portion 41b of the transmission member 4b, the detected member 6b contacts the detection unit 100 for a second time, and detection is completed.

In some embodiments, the developing cartridge is further provided with a resilient reset member that applies a resilient force to the detected member 6b, enabling the detected

member 6b to return to the initial state. Specifically, the resilient reset member may be a compression spring that supports the force receiving portion 61b of the detected member 6b in the upward direction so that the detected member 6b remains at in the initial position.

In some other embodiments, the above variations are combined as needed for the design.

Embodiment 3

This embodiment is an improvement based on Embodiment 1 and its variations, the shape and structure of the developing cartridge in Embodiment 3 are essentially the same as the developing cartridge in Embodiment 1, and the same parts will not be repeated, and the following mainly describes the differences.

As shown in FIGS. 10 and 11, in this embodiment, the rotational axis of the cam member 3c and that of the coupling member 21c are intersecting (including cases where they intersect in the same plane and where their projections intersect on the same plane).

Specifically, the rotational axis of the cam member 3c is set perpendicular to the rotational axis of the coupling member 21c, and the second gear portion 32c of the cam member 3c is a first bevel gear teeth portion which engages with a second bevel gear teeth portion 38c provided on the stirring member gear. The cam portion 33c of the cam member 3c is provided on the upper side of the cam member 3c, and the cam portion 33c extends outwardly in the radial direction from the main body portion 31c.

In this embodiment, the clutch mechanism includes a missing tooth portion 37c provided on the outer circumferential surface of the main body portion 31c of the cam member 3c, and when the missing tooth portion 37c rotates to face the second bevel gear teeth portion 38c, the transmission of the drive force between the second bevel gear teeth portion 38c and the first bevel gear teeth portion 32c is interrupted.

The force receiving portion 41c of the transmission member 4c is located closer to the second side wall 12c compared to the cam portion 33c. In this embodiment, when the developing cartridge is not in use, the transmission member 4c is in the first position (the position shown in FIG. 10), and the force receiving portion 41c abuts against the root portion of the cam portion. When the second gear portion 32c of the cam member 3c receives the drive force and rotates, the cam portion 33c pushes the force receiving portion 41c, causing the transmission member 4c to slide to the right, driving the detected member 6c to rotate, thereby triggering the detection unit 100 of the imaging apparatus. As shown in FIG. 11, the transmission member 4c is in the second position. As the cam member 3c continues rotating, the force receiving portion 41c moves from the top of the cam portion 33c towards its root, the transmission member 4c slides to the left under the action of the elastic restoring force of the resilient member 5c and drives the detected member 6c to pivot, and the detected member 6c disengages from the detection unit 100, and detection is completed.

In some embodiments, the second bevel gear teeth portion may be provided on the coupling member 21c, the development roller gear 22c, the powder feed roller gear 23c, or the idler wheel 24c.

In some embodiments, the force receiving portion 41c of the transmission member 4c is located further away from the second side wall 12c compared to the cam portion.

In some other embodiments, the above variations are combined as required by the design.

Embodiment 4

This embodiment is an improvement based on Embodiment 1 and its variations, the shape and structure of the developing cartridge in Embodiment 4 are essentially the same as the developing cartridge in Embodiment 1, and the same parts will not be repeated, and the following mainly describes the differences.

As shown in FIGS. 12a and 12b, in this embodiment, the transmission member 4d is a pivoting member, at least a portion of which is movable along the longitudinal direction L of the cartridge body 1d.

The transmission member 4d comprises a force receiving portion 41d and a rod portion 42d. The middle portion of the rod portion 42d is connected to the cartridge body 1d in a manner that allows it to pivot upwardly and downwardly, such a connection can be achieved by means of a shaft portion and a shaft bore. The force receiving portion 41d is provided at the first end of the rod portion 42d, and it is positioned above the rotational axis of the main body portion 31d to enable the cam portion to push the force receiving portion 41d upwardly.

The driving member is a cam member 3d, the rotational axis of the cam member 3d is set in parallel to the rotational axis of the coupling member 21d, and the cam portion protrudes in the radial direction from the main body portion 31d. In this embodiment, the cam member 3d has two cam portions: a first cam portion 33d and a second cam portion 34d. A root portion of the cam portion is formed between the first cam portion 33d and the second cam portion 34d.

The resilient member 5d is supported at the second end of the rod portion 42d and is provided on the lower side of the second end of the rod portion 42d.

The detected member 6d is fixedly connected to the second end of the transmission member 4d, enabling it to pivot with the pivoting motion of the transmission member 4d.

The process by which the developing cartridge is detected by the detection unit 100 of the imaging apparatus will now be described with reference to FIGS. 12a and 12b.

In this embodiment, when the developing cartridge is not in use, the transmission member 4d is in the second position (as shown in FIG. 12a), the force receiving portion 41d abuts against the top of the first cam portion 33d, the resilient member 5d is compressed, and the detected member 6d has not triggered the detection unit.

When the imaging apparatus begins to operate, as the cam member 3d rotates, the force receiving portion 41d of the transmission member 4d moves towards the root along the first guiding surface 35d of the first cam portion 33d, and under the action of the elastic restoring force of the resilient member 5d, the second end of the rod portion 42d lifts upwardly and drives the detected member 6d upwardly and the detected member 6d then triggers the detection unit in the imaging apparatus, and the transmission member moves to the first position (the position shown in FIG. 12b).

As the cam member 3d continues rotating, the second cam portion 34d pushes the force receiving portion 41d of the transmission member 4d. As a result, the force receiving portion 41d first moves upwardly and then downwardly. Synchronously, the detected member 6d moves downwardly to disengage from the detection unit 100 and then upwardly contacting the detection unit 100 again, thereby completing the detection.

FIG. 13a illustrates the positional state of the transmission member 4d when it is in the second position; and FIG. 13b illustrates the positional state of the transmission member 4d when it is in the first position. As shown in FIG. 13a, when 5 the transmission member 4d is in the second position, the distance from one end of the transmission member 4d to the pivoting center along the longitudinal direction L of the developing cartridge is d2. When the transmission member 4d pivots from the second position to the first position, as 10 shown in FIG. 13b, the distance from the same end of the transmission member 4d to the pivoting center along the longitudinal direction L of the developing cartridge is d3, and d3 is smaller than d2, and the movement distance of this 15 end of the transmission member 4d along the longitudinal direction of the developing cartridge is the difference between d2 and d3.

In some embodiments, the force receiving portion 41d may also be provided on the lower side of the rotational axis of the main body portion 31d, and the detection unit 100 is triggered when the detected portion 63d moves downward.

In some other embodiments, the above variations are combined as required by the design.

Embodiment 5

This embodiment is an improvement based on Embodiment 4 and its variations, and the shape and structure of the developing cartridge in Embodiment 5 are essentially the same as the developing cartridge in Embodiment 4, and the 30 same parts will not be repeated, and the following mainly describes the differences.

As shown in FIGS. 14a and 14b, in this embodiment, the transmission member 4e is a pivoting member configured to pivot in a front-rear direction of the developing cartridge, 35 and at least a portion of the pivoting member is movable along the longitudinal direction L of the cartridge body 1e.

The transmission member 4e includes a force receiving portion 41e and a rod portion 42e, and the middle portion of the rod portion 42e is connected to the cartridge body 1e in 40 a front-rear pivotal manner, such a connection can be achieved, for example, through a shaft portion and a shaft bore. The force receiving portion 41e is provided at the first end of the rod portion 42e in front of a rotational axis of the cam member 3e, to enable the cam portion to push the force receiving portion 41e forward.

The rotational axis of the cam member 3e is set parallel to the rotational axis of the coupling member 21e, and the cam portion protrudes in the radial direction from the main body portion 31e. In this embodiment, the cam member 3e likewise has a first cam portion 33e and a second cam portion 34e, and a root portion of the cam portion is formed between the first cam portion 33e and the second cam portion 34e.

The resilient member 5e supports the first end of the rod 55 portion 42e and is provided on the front side of the first end of the rod portion 42e, and the detected member 6e is fixedly connected to the second end of the rod portion 42e and is configured to pivot with the pivoting motion of the transmission member 4e.

60 The process by which the developing cartridge is detected by the detection unit 100 of the imaging apparatus will now be described with reference to FIGS. 14a and 14b.

In this embodiment, when the developing cartridge is not in use, the transmission member 4e is in a first position (the 65 position illustrated in FIG. 14a), the force receiving portion 41e abuts against the circumferential surface of the cam body, and the resilient member 5e is not compressed.

When the imaging apparatus begins to operate, the second gear portion $32e$ of the cam member $3e$ receives a drive force and rotates. Driven by the first cam portion $33e$, the first cam portion $33e$ pushes the force receiving portion $41e$ causing the force receiving portion $41e$ to move towards the front as shown in FIG. 14b, the second end of the transmission member $4e$ pivots towards the rear, and the detected member $6e$ moves towards the rear with the second end of the rod portion $42e$ to contact the detection unit 100 .

When the force receiving portion $41e$ of the transmission member $4e$ crosses the top of the first cam portion $33e$, under the action of the elastic restoring force of the resilient member $5e$, the first end of the rod portion $42e$ moves towards the rear of the developing cartridge, and the second end of the rod portion $42e$ drives the detected member $6e$ in the direction of away from the detection unit 100 towards the front, and when the second cam portion $34e$ pushes the force receiving portion $41e$, the action process of the transmission member $4e$ and the detected member $6e$ is the same as when the first cam portion $33e$ pushes the force receiving portion $41e$, resulting in the detection unit 100 of the imaging apparatus being triggered again, thereby completing the detection.

FIG. 15a illustrates the positional state of the transmission member $4e$ when it is in the first position; and FIG. 15b illustrates the positional state of the transmission member $4e$ when it is in the second position. As shown in FIG. 15a, when the transmission member $4e$ is in the first position, the distance from one part a of the transmission member $4e$ to the pivoting center along the longitudinal direction L of the developing cartridge is $d4$. When the transmission member $4e$ pivots from the first position to the second position, as shown in FIG. 15b, the distance from the same part a of the transmission member $4e$ to the pivoting center along the longitudinal direction L of the developing cartridge is $d5$, and $d5$ is smaller than $d4$, and the movement distance of part a of the transmission member $4e$ along the longitudinal direction L of the developing cartridge is the difference between $d4$ and $d5$.

In some embodiments, the cam portion may also be configured to push the transmission member $4e$ rearwardly.

In some other embodiments, the above variations are combined as required by the design.

Embodiment 6

As shown in FIGS. 16 to 22, in Embodiment 6, the cartridge body $1f$ of the developing cartridge $10f$ is substantially cuboid in shape, with a first side wall $11f$ and a second side wall $12f$ provided externally along its longitudinal direction, and internally it is provided with a powder compartment for accommodating developer, a development roller $14f$, a powder feed roller, and a stirring member $15f$. The development roller $14f$ is provided on the front side of the developing cartridge $10f$ in the mounting direction P towards the imaging apparatus. It is exposed from the front side of the cartridge body $1f$ and faces the photoconductor drum when mounted in the imaging apparatus for performing development. The powder feed roller faces the development roller $14f$ and is configured to deliver developer to the development roller $14f$. The stirring member $15f$ is configured to stir the developer accommodated in the powder compartment.

The drive force receiving unit $2f$ is provided at the first side (or the first end of the developing cartridge) along the longitudinal direction of the cartridge body $1f$ for receiving a drive force from a drive transmission member of the

imaging apparatus and to transmit a rotational drive force to rotating members such as the development roller $14f$. Specifically, in this embodiment, the drive force receiving unit $2f$ includes a coupling member $21f$, a development roller gear $22f$, a powder feed roller gear $23f$, a stirring member gear $24f$, and an idler wheel $25f$.

As shown in FIGS. 17 and 18, the coupling member $21f$ is rotatably supported on the first side wall $11f$ of the cartridge body $1f$, and its rotational axis L1 extends along the longitudinal direction of the developing cartridge $10f$ parallel to the rotational axis L2 of the development roller $14f$. The coupling member $21f$ is provided with a drive force receiving portion $211f$ and a gear portion $212f$, wherein the drive force receiving portion $211f$ is coupled to the drive transmission member and receives the drive force, and the gear portion $212f$ is configured to engage with the development roller gear $22f$, the powder feed roller gear $23f$, and the idler wheel $25f$ for transmitting rotational drive force to them. The development roller gear $22f$ and the powder feed roller gear $23f$ are provided at the ends of the development roller $14f$ and the powder feed roller, respectively, to drive the rotation of these components. The stirring member gear $24f$ is provided at an end portion of the stirring member $15f$ and engages with the idler wheel $25f$ to drive the stirring member $15f$ to rotate.

As shown in FIGS. 20 to 22, the developing cartridge $10f$ includes the detected member $6f$ and a support member, and the support member in this embodiment is a rotating body $61f$, the rotating body $61f$ is provided at a second end along the longitudinal direction of the developing cartridge $10f$ (located opposite to the first end along the longitudinal direction of the developing cartridge $10f$), the rotating body $61f$ is configured to rotate by receiving a drive force transmitted from the coupling member $21f$, and the rotating body $61f$ has a rotational axis L3 that intersects (either spatially or planarly) with the rotational axis L1 of the coupling member $21f$ and the rotational axis L2 of the development roller $14f$, i.e., the rotational axis L3 is not parallel to the rotational axis L1 of the coupling member $21f$. In the projection on the plane parallel to the rotational axis L1 and the rotational axis L3, the rotational axis L3 of the rotating body $61f$ intersects with the rotational axis L1 of the coupling member $21f$. The rotating body $61f$ includes a second mounting portion $612f$ and a rotating support portion $612f$, which allows it to be rotatably supported on the developing cartridge $10f$.

The detected member $6f$ is movable with the rotation of the rotating body $61f$. For example, the detected member of may rotate or pivot with the rotation of the rotating body $61f$, and is configured to contact a transmission mechanism to cause this transmission mechanism to rotate or pivot, thereby enabling the detected member of to be detected by a detection unit in the imaging apparatus.

As shown in FIGS. 17 to 22, the developing cartridge $10f$ of the present embodiment further comprises a driving member $3f$ and a transmission member. The driving member $3f$ comprises a first transmission body $31f$ and a second transmission body $32f$, wherein the second transmission body $32f$ is configured to receive a drive force from the drive force receiving unit $2f$, and the first transmission body $31f$ receives a drive force from the second transmission body $32f$, the transmission member is a flexible transmission member $4f$, and the flexible transmission member $4f$ connects the first transmission body $31f$ to the rotating body $61f$, to drive the rotation of the rotating body $61f$.

Specifically, in this embodiment, the first transmission body $31f$ is provided with a first rotational force receiving portion $311f$ for receiving a rotational force and a first

mounting portion $312f$ for mounting the flexible transmission member $4f$, the first rotational force receiving portion $311f$ may be a gear portion, and the first mounting portion $312f$ is preferably a shaft portion of the first transmission body $31f$. Preferably, the rotational axis $L4$ of the first transmission body $31f$ is perpendicular (including spatially perpendicular and planarly perpendicular) to the rotational axis $L1$ of the coupling member $21f$ and the rotational axis $L2$ of the development roller $14f$, and is parallel to the mounting direction P of the developing cartridge $10f$.

The second transmission body $32f$ is provided with a second rotational force receiving portion $321f$ and a rotational force transmitting portion $322f$, and a rotational axis $L5$ of the second transmission body $32f$ is parallel to the rotational axis $L1$ of the coupling member $21f$ and perpendicular to the rotational axis $L4$ of the first transmission body $31f$. The second rotational force receiving portion $321f$ is configured to receive a rotational drive force from the drive force receiving unit $2f$. The rotational force transmitting portion $322f$ is connected to the first rotational force receiving portion $311f$ to transmit rotational drive force to the first transmission body $31f$. The second rotational force receiving portion $321f$ may be a gear portion that meshes with the stirring member gear $24f$, and the rotational force transmitting portion $322f$ may be a screw portion that cooperates with the first rotational force receiving portion $311f$.

Preferably, the first transmission body $31f$ and the second transmission body $32f$ are both rotatably provided on a first side of the cartridge body $1f$ (a first end of the developing cartridge) on the same side of the cartridge body $1f$ as the coupling member $21f$. The first rotational force receiving portion $311f$ of the first transmission body $31f$ is preferably a first gear portion $311f$, and the first mounting portion $312f$ is an annular groove provided on the shaft portion of the first transmission body $31f$, and the annular groove rotates together with the rotation of the first gear portion $311f$.

The second rotational force receiving portion $321f$ of the second transmission body $32f$ is preferably a second gear portion $321f$, and the rotational force transmitting portion $322f$ is preferably a screw portion $322f$ that engages with the first gear portion $311f$.

The second transmission body $32f$ is rotatably supported on the first side wall $11f$ with its second gear portion $321f$ engaged with the stirring member gear $24f$ to receive the drive force, and the first gear portion $311f$ is disposed on the upper side of the screw portion $322f$ and engages with it to receive a drive force. Along the mounting direction P for the developing cartridge $10f$, the first mounting portion $312f$ of the first transmission body $31f$ is located at the downstream side of the first gear portion $311f$.

The flexible transmission member $4f$ is configured to connect the first transmission body $31f$ to the rotating body $61f$ to transmit a drive force to the rotating body $61f$. The flexible transmission member $4f$ is movable along the longitudinal direction L of the developing cartridge $10f$. As an example of the flexible transmission member $4f$, it is preferably a flexible belt. The flexible belt may be a leather belt, a rubber belt, or the like. One end of the flexible belt is fitted onto the first mounting portion $312f$ of the first transmission body $31f$, and the other end is fitted onto the second mounting portion $611f$ of the rotating body $61f$ (which may be a shaft or an annular groove on the rotating body $61f$). This arrangement allows the flexible belt to rotate when the first transmission body $31f$ rotates, which in turn drives the rotating body $61f$. The detected member $6f$ moves with the rotation of the rotating body $61f$.

The flexible transmission member $4f$ is configured to move along the longitudinal direction L of the developing cartridge $10f$ while rotating. After the flexible transmission member $4f$ has moved for a predetermined distance, each portion of the flexible transmission member $4f$ is configured to move along the longitudinal direction L of the developing cartridge $10f$ for this same distance. In other words, as the flexible transmission member $4f$ rotates as a whole, each portion of the flexible transmission member $4f$ also moves along the longitudinal direction L of the developing cartridge $10f$.

The flexible belt is configured to have friction with the first transmission body $31f$ and the second mounting portion $611f$ of the rotating body $61f$. This allows the first transmission body $31f$ to drive the flexible belt, and in turn to drive the rotating body $61f$. Such friction may be achieved by providing rough surfaces on the flexible belt, the first transmission body $31f$, and the rotating body $61f$, by adopting a mating structure of protrusions and concave portions, or by using a toothed mating structure.

In this embodiment, the first transmission body $31f$, the second transmission body $32f$, and the flexible transmission member $4f$ form a transmission direction-change unit, which is configured to connect the drive force receiving unit $2f$ to the rotating body $61f$ to achieve the transmission of the drive force. The transmission direction-change unit is configured to transmit the rotational force of a first object (e.g., the drive force receiving unit) in a first direction to a second object to enable movement of the second object (e.g., the detected member) in a second direction, and the rotational axis of the first object intersects with the movement direction of the second object, and this intersection may be spatial or planar. The movement may be either a linear motion or a rotational or curvilinear motion.

Further, referring to FIG. 21, in this embodiment, the transmission direction-change unit further comprises a direction change body $64f$, specifically the direction change body may be a second support member. For example, the flexible transmission member in the form of flexible belt is supported by this second support member to bend downwardly from the upper side to change its direction. Optionally, the direction change body $64f$ may also be a roller.

In this embodiment, the detected member $6f$ is provided on an outer surface of the flexible transmission member in the form of flexible belt, and protrudes from this outer surface. There may be one or more detected members $6f$. In this embodiment, multiple detected members $6f$ are spaced at predetermined distances apart. This arrangement allows that when the flexible belt drives the rotating body $61f$ to rotate, the detected members of may contact the transmission mechanism of the imaging apparatus, thereby causing this transmission mechanism to pivot. Consequently, the imaging apparatus can detect the developing cartridge $10f$.

Optionally, the detected member $6f$ can also be provided on the rotating body $61f$, allowing it to rotate with the rotating body $61f$ and to contact the transmission mechanism. Alternatively, the detected member $6f$ may be removably mounted on the flexible belt or integrally molded with it being able to protrude from the surface of the flexible belt.

In this embodiment, the developing cartridge $10f$ may also include a first end cap $101f$ and a second end cap $102f$ disposed on the first side and the second side, respectively, of the cartridge body $1f$. The first end cap $101f$ covers an outer side of the drive force receiving unit $2f$, and the coupling member $21f$ of the drive force receiving unit $2f$ may be exposed through a first hole portion $1011f$ in the first end cap $101f$. The second end cap $102f$ covers the second side of

the cartridge body 1f, and the second end cap 102f is provided with an exposure portion 1021f through which the detected member 6f can be exposed. The rotating body 61f can be rotatably supported on the inner side of the second end cap 102f.

The process by which the developing cartridge 10f is detected by the detection unit in the imaging apparatus will now be described with reference to FIG. 16-FIG. 22.

The user installs the developing cartridge 10f into the imaging apparatus, and the coupling member 21f is coupled to a drive transmission member of the imaging apparatus. When the imaging apparatus starts to operate, the coupling member 21f receives a rotational drive force and rotates, transmitting this rotational force to the second transmission body 32f. The second transmission body 32f then rotates and drives the rotation of the first transmission body 31f through its screw portion 322f. Subsequently, the rotation of the first transmission body 31f then drives the rotation of the flexible belt 4f, which in turn rotates the rotating body 61f of the detected mechanism. As a result, the detected member of on the flexible belt 4f contacts the transmission mechanism of the imaging apparatus and is then detected by the imaging apparatus.

In some other embodiments, the second transmission body 32f may receive a rotational drive force from the coupling member 21f, the development roller gear 22f, the powder feed roller gear 23f, or the idler wheel 25f, in addition to receiving a rotational drive force from the stirring member gear 24f.

In some other embodiments, the second transmission body 32f may also be one of the coupling member 21f having a screw portion 322f, the development roller gear 22f, the powder feed roller, or the powder feed roller gear 23f.

In some other embodiments, the rotational force transmitting portion and the first rotational force receiving portion may also form a bevel gear teeth transmission structure (or bevel gear teeth portion), i.e., both the first transmission body 31f and the second transmission body 32f include bevel gear structures, replacing the transmission from the screw portion to the gear with a transmission using beveled teeth. Specifically, the rotational force transmitting portion is in the form of a conical body, the top of this conical body is further away from the first side wall 11f than the bottom, and its sides are provided with conical teeth, and the first rotational force receiving portion is provided with conical teeth, with its rotational axis configured to be perpendicular to the rotational axis of the rotational force transmitting portion.

In some other embodiments, the rotational force transmitting portion and the first rotational force receiving portion may also be connected to each other by a linkage structure such that the rotational axes of the first transmission body and the second transmission body intersect (that is, not parallel).

In some other embodiments, the driving member and the transmission direction-change unit may also be designed without the second transmission body. In this case, the rotational axis of the first transmission body would be configured to be parallel to the rotational axis of the coupling member, with the flexible belt fitted to the first mounting portion of the first transmission body, and its other end fitted to the second mounting portion of the rotating body. Preferably, with the first transmission body and the rotating body at either end, the flexible belt can be divided into a first belt section and a second belt section, and in this variation, the first belt section and the second belt section are non-parallel and are in a cross-over state to drive the rotating body whose

rotational axis intersects the rotational axis of the first transmission body to rotate. Optionally, in this configuration, the first transmission body may be the coupling member with a first mounting portion, the development roller gear, the powder feed roller gear, the stirring member gear, or the idler wheel.

In some other embodiments, the flexible transmission member may also be a chain, a rubber band, etc.

In some other embodiments, the support member may 10 also be a component that is fixed to the cartridge body. For example, the rotating body 61f in this embodiment may be replaced with a fixed member. In this case, the fixed member would be fixedly connected to the cartridge body 1f at both 15 ends with the fixed member having a smooth surface. The flexible belt would be fitted on this smooth surface allowing it to slide relative to the fixed member, thereby enabling the detected members disposed on the flexible belt to move and contact the transmission mechanism of the imaging apparatus.

In some other embodiments, depending on the type of 20 imaging apparatus, the rotational axis L3 of the rotating body 61f and the rotational axis L1 of the coupling member 21f may form different angles, such as 90 degrees, 60 degrees, or 30 degrees. This configuration significantly 25 reduces the requirements for precision and improves design flexibility.

In some other embodiments, depending on the type of 30 imaging apparatus, the rotating body 61f may be provided in different positions on the developing cartridge such as on the first side, upper side, lower side or rear side of the cartridge body 1f, which greatly improves the flexibility of the design.

In some other embodiments, the developing cartridge may 35 further comprise a transmission interrupting mechanism (also referred to as a clutch mechanism), the transmission interrupting mechanism is configured to interrupt the drive force transmitted from the first transmission body to the detected member, thereby causing the detected member to stop moving. Specifically, for a structure in which the first 40 transmission body and the flexible belt are driven by friction, the transmission interrupting mechanism may include a smooth surface disposed on the inner side of the flexible transmission member in the form of flexible belt. When this smooth surface moves to a position contacting the first transmission body 31f, the first transmission body 31f becomes 45 unable to transmit the drive force to the flexible belt, resulting in the cessation of the flexible belt's rotation.

In some other embodiments, the above variations may be combined as needed to meet the design requirements.

The developing cartridge having the above-described 50 structure utilizes the flexible transmission member for drive force transmission, this allows for more diverse positioning options for the detected member. Moreover, the rotational axis L3 of the rotating body can be set at an angle to the rotational axis L1 of the coupling member 21f, i.e., it does 55 not need to be parallel, with the angle adjustable as required. This also enhances the flexibility in positioning of the detection unit in the imaging apparatus. The developing cartridge 10f having the above-described structure effectively solves the problem of speed differences arising from 60 long-distance transmission by adopting the flexible transmission member 4f.

Compared to the direct transmission of drive force through gears to the rotating body 61f, the developing cartridge 10f having the above structure requires less stringent 65 consideration of transmission ratios. When the rotational speed of the rotating body 61f needs to be controlled, the gear-based design requires a plurality of gears for

deceleration, which would increase the number of parts and raises the production costs. With the flexible transmission member 4f connecting the rotating body 61f and the first transmission body 31f, when the speed of transmission needs to be reduced, it is only necessary to adjust the diameters of the rotating body 61f and the first transmission body 31f, greatly reducing design costs.

The developing cartridge 10f having the structure described above allows for multiple contacts of the transmission mechanism of the imaging apparatus. This can be achieved by providing a plurality of detected members of on the flexible transmission member or on the rotating body 61f, or by increasing the number of revolutions. When longer intervals between each contact are required, such a structure is also advantageous.

Embodiment 7

As shown in FIGS. 23 and 24, the shape and structure of the developing cartridge in the present embodiment are basically the same as those of the developing cartridge in Embodiment 6, and the similarities will not be repeated, and the following mainly describes the different aspects.

The flexible transmission member in the present embodiment is a flexible cord 4/1, one end of the flexible cord 4/1 is wound on or attached to the first transmission body 31f, and the other end is wound on the rotating body 61f, and the number of rotational revolutions of the rotating body 61f can be controlled by adjusting the number of turns of the flexible cord 4/1 wound on the rotating body 61f. The flexible cord 4/1 is wound in opposite directions on the first transmission body 31f and the rotating body 61f.

When the developing cartridge 10f is mounted in the imaging apparatus and the coupling member 21f receives the drive force and rotates, the first transmission body 31f receives the drive force and rotates and pulls the flexible cord 4/1. Due to the pulling of the flexible cord 4/1, the rotating body 61f starts to rotate, which causes the detected member 6f disposed on the rotating body 61f to contact the transmission mechanism of the imaging apparatus. In this structure, as the first transmission body 31f and the rotating body 61f rotate, the number of turns wound on the first transmission body 31f increases while the number of turns wound on the rotating body 61f decreases.

In some other embodiments, a direction changing body may also be provided between the first transmission body 31f and the rotating body 61f to change the direction of the transmission. Specifically, the direction changing body may be a roller around which the flexible cord 4/1 changes the direction of the transmission before connecting to the rotating body 61f. Optionally, the direction changing body may also be a fixed second support member with the second support member acting as a fulcrum around which the flexible cord 4/1 wraps around to change its direction.

In some other embodiments, the flexible transmission member may also be a metal wire such as steel wire, iron wire, or other metal wires, or a chain.

In some other embodiments, the developing cartridge may further comprise a transmission interrupting mechanism (clutch mechanism), and the transmission interrupting mechanism is configured to interrupt the drive force transmitted from the drive force receiving unit to the detected member, causing the detected member to stop moving. In this embodiment, the flexible cord or steel wire may not be attached to the rotating body 61f. As a result, as the rotating body 61f rotates, eventually the flexible cord falls off the

rotating body 61f, causing the rotating body to stop rotating, and the detected member stops rotating.

For other structures and variations of the developing cartridge in Embodiment 7, please refer to the description in Embodiment 6, which will not be repeated here.

Embodiment 8

This embodiment is an improvement based on Embodiment 1 and its variations. The shape and structure of the developing cartridge in Embodiment 8 are essentially the same as the developing cartridge in Embodiment 1. The same parts will not be described again; the following mainly focuses on the differences.

As shown in FIG. 25, in this embodiment, the driving member is a grooved cam wheel member 3g having a rotational axis parallel to the rotational axis of the coupling member. The grooved cam wheel member 3g includes a cylindrical main body portion 31g, a guide groove 311g provided on a circumferential outer surface of the main body portion 31g, and a second gear portion 32g that is configured to engage with the drive force receiving unit.

The action portion of the driving member is provided within the guide groove 311g (or forms a portion of the guide groove), and the force receiving portion 41g of the transmission member 4g is embedded into the guide groove 311g along the radial direction of the main body portion 31g and is configured to move along the guide groove 311g as the grooved cam wheel member 3g rotates. Preferably, the embedded portion may be in the form of a cylinder that matches the guide groove 311g.

In this embodiment, there are two action portions: a first action portion 33g and a second action portion 34g, both having the same shape and structure.

Taking the first action portion 33g as an example, it extends along a direction away from the first side wall along the direction of the rotational axis of the grooved cam wheel member 3g in order to push the force receiving portion 41g of the transmission member 4g when the grooved cam wheel member 3g rotates.

The process by which the developing cartridge is detected by the detection unit in the imaging apparatus will now be described with reference to FIG. 25.

In this embodiment, when the developing cartridge is not in use, the force receiving portion 41g of the transmission member 4g abuts against the side wall 312g of the guide groove 311g, and the detected member 6g is in a state separated from the detection unit.

When the grooved cam wheel member 3g receives the drive force and rotates, the force receiving portion 41g is pushed by the first action portion 33g first moving from the root to the top of the first action portion 33g, then moving from the top back to the root of the first action portion 33g. As a result, the transmission member 4g slides to the left and then to the right, and synchronously, the detected member 6g rotates and then returns to its initial position after contacting the detection unit in the imaging apparatus. As the grooved cam wheel member 3g continues to rotate, the second action portion 34g pushes the force receiving portion 41g and repeats the cooperative action process between the first action portion 33g and the force receiving portion 41g. This allows the detected member 6g to contact the detection unit again and complete the detection.

The developing cartridge having the above structure allows for the omission of the resilient member. The trans-

mission member relies on the guide groove to prevent the force receiving portion from detaching from the grooved cam wheel member 3g.

Embodiment 9

This embodiment is an improvement based on Embodiment 4 and its variations, and the shape and structure of the developing cartridge in Embodiment 9 are essentially the same as the developing cartridge in Embodiment 4, and the same parts will not be repeated, and the following mainly describes the differences.

As shown in FIGS. 26 and 27, in this embodiment, the driving member is a grooved cam wheel member 3h having a rotational axis parallel to the rotational axis of the coupling member. The grooved cam wheel member 3h comprises a cylindrical main body portion 31h. A guide groove 311h is provided on an end face of the main body portion 31h near the first side wall, and a second gear portion 32h configured to engage with the drive force receiving unit is provided on its circumferential outer face.

The action portion of the driving member is provided within the guide groove 311h (or forms a portion of the guide groove). The force receiving portion 41h of the transmission member 4h is embedded into the guide groove 311h along the direction of the rotational axis of the main body portion 31h and is configured to move along the guide groove 311h when the grooved cam wheel member 3h rotates.

In this embodiment, there are two action portions: a first action portion 33h and a second action portion 34h with the same shape and structure. Taking the first action portion 33h as an example, the first action portion 33h extends along the radial direction from the main body portion 31h in order to push the force receiving portion 41h of the transmission member 4h when the grooved cam wheel member 3h rotates.

The transmission member 4h is configured to pivot up and down around a shaft portion 46h located in its center, which includes a rod portion 42h and a force receiving portion 41h, and the end of the rod portion 42h located remote from the grooved cam wheel member 3h is fixedly connected to the detected member 6h.

The process by which the developing cartridge is detected by the detection unit in the imaging apparatus will now be described with reference to FIGS. 26 and 27.

In this embodiment, when the developing cartridge is not in use, the transmission member 4h is in the second position where the force receiving portion 41h is located at the top of the first action portion 33h, and the detected member 6h is in a state where it has not contacted the detection unit.

When the grooved cam wheel member 3h receives a drive force and rotates, the force receiving portion 41h moves from the top of the first action portion 33h towards the root of the first action portion 33h, the first end of the rod portion 42h moves downwardly, and the second end of the rod portion 42h lifts upwardly and drives the detected member 6h upwardly. As a result, the detected member 6h triggers the detection unit in the imaging apparatus.

As the second action portion 34h pushes the force receiving portion 41h of the transmission member 4h, the force receiving portion 41h first moves upwardly and then downwardly, and synchronously, the detected member 6h moves downwardly to disengage from the detection unit and then moves upwardly to contact the detection unit again, thereby completing the detection.

The developing cartridge having the above-described structure allows for the omitting of the resilient member, and

the transmission member relies on the restrictive effect of the guide groove to prevent it from disengaging from the grooved cam wheel member 3h.

Optionally, the number and shape of the action portions 5 may be varied as needed. For example, one or more action portions may be provided, or a plurality of action portions may have different shapes.

Embodiment 10

This embodiment is an improvement based on Embodiment 1 and its variations, and the shape and structure of the developing cartridge 10j in Embodiment 10 are essentially the same as that of the developing cartridge 10a in Embodiment 1, and the same parts will not be repeated, and the following mainly describes the differences.

As shown in FIGS. 28 to 34, the driving member in the present embodiment is configured as a cam member, and the developing cartridge 10j is provided with a clutch mechanism for interrupting the transmission of the drive force to the detected member 6j at a predetermined time. The clutch mechanism includes a forcing structure and a retracting structure, the forcing structure is designed to force at least a portion of the cam member 3j to move, and the retracting structure provides a displacement space for this portion of the cam member to move. Specifically, the retracting structure includes a first protruding portion 81j provided at the end of the cam member 3j near the first side wall 11j and a yielding portion 82j disposed on the support member 87j. Specifically, the yielding portion is in the form of an opening 82j.

The first protruding portion 81j can move against the surface of the support member 87j, and when the first protruding portion 81j moves to the opening 82j, it falls into the opening 82j under the action of the forcing structure, causing the cam member 3j to move.

The support member 87j is fixedly connected to the first side wall or replaces it. The forcing structure includes a second protruding portion 83j provided on the first end cap 40 101j and a third protruding portion 85j provided on the end of the cam member 3j away from the first side wall 11j. The second protruding portion 83j and the third protruding portion 45 85j protrude in opposite directions. This arrangement allows that upon rotation of the cam member 3j, the third protruding portion 85j moves along the pressure surface of the second protruding portion 83j towards the top of the second protruding portion 83j, thereby forcing the cam member 3j to move along the longitudinal direction of the developing cartridge 10j and interrupts the transmission of the drive force.

The interplay between the forcing structure and the retracting structure is such that the first protruding portion 81j moves first to the opening 82j before the second protruding portion 83j pushes the third protruding portion 85j. 55 Alternatively, as the second protruding portion 83j pushes the third protruding portion 85j, the first protruding portion 81j may move to the opening 82j at the same time. This structure allows the developing cartridge 10j to omit the resilient member. The structure is simpler, and assembly is 60 more convenient.

The cam member 3j in this embodiment further includes a main body portion 31j, a cam portion 33j, and a rotational force receiving portion 313j, the main body portion 31j is substantially cylindrical in shape, with a flange portion 311j provided on its outer circumference. A third protruding portion 85j protrudes outwardly from the side of the cam member 3j away from the first side wall 11j, and is designed

31

to abut against the inner side of the first end cap **101j**. The first protruding portion **81j** protrudes from the main body portion **31j** in a direction towards the first side wall **11j**. The cam portion **33j** is provided on a side of the flange portion **311j** proximate to the first side wall **11j**, and protrudes in the direction towards the first side wall **11j** in order to form a fit with the transmission member **4j**. The rotational force receiving portion **313j** is configured to protrude from the circumferential outer side of the main body portion **31j** in the radial direction of the main body portion **31j** to receive the drive force. The second gear member **32j** includes a hollow portion **321j**, a gear portion **322j**, and a rotational force transmitting portion **323j**, and the hollow portion **321j** is cylindrically hollow, which is configured to be fitted onto the outer side of the cam member **3j**.

The rotational force transmitting portion **323j** protrudes from the inner wall of the hollow portion **321j** in the radial direction of the second gear member **32j**, and is configured to engage with the rotational force receiving portion **313j** of the cam member **3j**. This allows the rotational force transmitting portion **323j** to drive the rotational force receiving portion **313j** to rotate when the second gear member **32j** rotates, and when the cam member **3j** moves along the longitudinal direction of the developing cartridge **10j**, the rotational force transmitting portion **323j** and the rotational force receiving portion **313j** become disengaged along the longitudinal direction of the developing cartridge, thereby interrupting the transmission of the rotational drive force.

In this embodiment, the developing cartridge further comprises a restriction portion that restricts the movement of the second gear member **32j**. Specifically, the restriction portion is in the form of a protrusion **116j** disposed on the first side wall **11j**, the protrusion **116j** abuts against the end of the second gear member **32j** closest to the first side wall **11j**. It is configured to restrict the second gear member **32j** from moving with the cam member **3j** during relative movement between the cam member **3j** and the second gear member **32j**. This enables a better separation between the rotational force transmitting portion **323j** and the rotational force receiving portion **313j**. Preferably, a plurality of restriction portions may be provided on both the end cap and the side wall.

The upper side of the cartridge body **1j** is provided with a sliding groove portion **16j**, and the transmission member **4j** is slidably accommodated in the sliding groove portion **16j**. Specifically, the upper surface of the transmission member **4j** is flush with or lower than the upper surface of the cartridge body **1j**.

The developing cartridge **10j** further comprises a covering portion **7j** that at least partially covers the transmission member **4j**, the covering portion **7j** in the present embodiment is in the form of an elongated strip that is configured to be snapped onto the cartridge body **1j** to cover the transmission member **4j**.

Specifically, the covering portion **7j** is provided with snap-fit portions **71j**, a first exposed portion **72j**, and a second exposed portion **73j** at its ends. The snap-fit portions **71j** disposed at the ends are snapped onto the cartridge body **1j** to secure the covering portion **7j**. The first exposed portion **72j** and the second exposed portion **73j** are configured as openings. One end of the transmission member **4j** can extend through the first exposed portion **72j** to cooperate with the cam member **3j**. The detected portion **63j** of the detected member **6j** can be exposed through the second exposed portion **73j** in order to cooperate with the detection unit in the imaging apparatus.

32

The detected member **6j** is supported on the second end of the covering portion **7j** in a manner allowing it to pivot in the up-down direction, and the second end of the covering portion **7j** is provided with an accommodating cavity **75j** to accommodate a portion of the detected member **6j**.

Specifically, the connection portion **62j** of the detected member **6j** is pivotally attached to the covering portion **7j**, the pivot axis of the connection portion **62j** is located above the force receiving portion **61j**. The detected portion **63j** is located below the pivot axis and below the transmission mechanism **200j** of the detection unit when mounted in the imaging apparatus. The detected portion **63j** can trigger the transmission mechanism **200j** when it pivots up and down.

In this embodiment, the second end of the transmission member **4j** further comprises a bending section **46j** which bends downwardly and connects to a drive portion **47j**. The drive portion **47j** of the transmission member **4j** extends along the longitudinal direction of the developing cartridge **10j**. The detected member **6j** is pivotally supported on the covering portion **7j**, and the force receiving portion **61j** is located below the pivot axis of the connection portion **62j**. When the drive portion **47j** of the transmission member **4j** triggers the force receiving portion **61j** of the detected member **6j**, the detected member **6j** pivots. As a result, the detected portion **63j** moves upwardly to trigger the detection unit so as to be able to be detected.

In this embodiment, when the developing cartridge **10j** is mounted in the imaging apparatus, the detected portion **63j** of the detected member **6j** is pressed against the transmission mechanism **200j** (which has a resilient force). As a result, the force receiving portion **61j** of the detected member **6j** pushes the transmission member **4j** towards the right side causing the transmission member **4j** to be firmly pressed against the flange portion **311j** of the cam member **3j**.

When the cam portion **33j** of the cam member **3j** pushes the transmission member **4j**, the transmission member **4j** moves towards the right side of the developing cartridge **10j**, which in turn pushes the detected member **6j** to pivot. Consequently, the detected portion **63j** of the detected member **6j** moves upwardly pushing against the rotation of the transmission mechanism **200j** of the detection unit enabling detection.

When the force receiving portion **41j** of the transmission member **4j** moves from the top of the cam portion **33j** towards the root, the detected member **6j** pushes the transmission member **4j** towards the left side of the developing cartridge **10j** under the action of the pressing force of the transmission mechanism **200j**.

The interaction of the components of the developing cartridge **10j** as it is detected by the imaging apparatus will now be described with reference to FIGS. **35a** to **35c**.

As shown in FIG. **35a**, when the developing cartridge **10j** is mounted in the imaging apparatus, the detected portion **63j** of the detected member **6j** is pressed by the transmission mechanism **200j**, the transmission member **4j** is pressed against the cam member **3j**, the third protruding portion **85j** is pressed against the inner wall of the first end cap **101j**, and the first protruding portion **81j** is pressed against the support member **87j**.

As shown in FIG. **35b**, when the cam portion **33j** pushes the transmission member **4j**. As a result, the transmission member **4j** pushes the detected member **6j**, and the detected portion **63j** of the detected member **6j** pivots upwardly and pushes the transmission mechanism **200j** enabling detection to occur.

As shown in FIG. **35c**, as the cam member **3j** rotates and the cam portion **33j** disengages from the transmission mem-

ber 4j, the transmission mechanism 200j elastically returns to press the detected portion 63j downwardly returning it to its initial position.

When the second protruding portion 83j pushes the third protruding portion 85j, the first protruding portion 81j is disposed at the opening 82j, thereby causing the cam member 3j to move to the right side. As a result, the rotational force receiving portion 313j of the cam member 3j is disconnected from the rotational force transmitting portion 323j of the second gear member 32j. Consequently, the transmission of the rotational force is interrupted and detection is completed.

With this structure, the developing cartridge 10j is provided with a sliding groove portion 16j, which improves the sliding effectiveness for the transmission member 4j and reduces the contacting and interference from the external environment. The developing cartridge 10j is provided with a covering portion 7j, which effectively protects the transmission member 4j and the detected member 6j from external collisions and interference. Moreover, the developing cartridge 10j in the present embodiment may omit the second end cap, reducing the number of parts and lowering production costs.

The developing cartridge 10j in the present embodiment further comprises a toner filling port 106j and a filling cover 107j. The toner filling port is disposed on the second side wall 12j of the developing cartridge and connects to the powder compartment. A chip and a chip holder may also be provided at the first end of the developing cartridge.

In some embodiments, the second protruding portion 83j can move along the pressing surface of the third protruding portion 85j to the top of the third protruding portion 85j to force the cam member 3j to move along the longitudinal direction of the developing cartridge 10j.

In some embodiments, the second gear member 32j may be integrally molded with or fixedly connected to the cam member 3j. In this case, when the cam member 3j moves along the longitudinal direction of the developing cartridge 10j, the second gear member 32j becomes disengaged from the idler wheel 24j of the drive force receiving unit, thereby interrupting the transmission of the drive force.

In some embodiments, the second protruding portion 83j may not be provided on the end cap, but instead on a component that is fixedly connected to the cartridge body.

In some embodiments, the detected portion may not contact the transmission mechanism 200j when the developing cartridge is first loaded into the imaging apparatus.

In some embodiments, the developing cartridge may comprise a resilient reset member that allows the transmission member to return to its initial position when not pushed by the cam portion.

In some embodiments, a rack structure may be used instead of a cam member. In this case, a protruding portion for driving the transmission member can be provided on the rack, and the rack receives the drive force through its tooth portions causing the rack to move. Subsequently, the protruding portion drives the transmission member to move.

In some embodiments, the forcing structure may also be a cooperative structure of a helical groove and a projection. For example, a helical groove extending along the longitudinal direction of the developing cartridge may be provided on the end cap, and a projection that cooperates with the helical groove may be provided on the cam member. In this arrangement, when the cam member rotates, the projection

moves along the helical groove resulting in movement along the longitudinal direction of the developing cartridge.

Embodiment 11

This embodiment is an improvement based on Embodiment 10 and its variations, and the shape and structure of the developing cartridge 10m in Embodiment 11 are essentially the same as the developing cartridge 10j in Embodiment 10, and the same parts will not be repeated, and the following mainly describes the differences.

As shown in FIGS. 36 and 37, the developing cartridge 10m comprises a clutch mechanism. Specifically, the clutch mechanism includes a notched portion 312m. The specific notched portion 312m is provided on the flange portion 311m, the cam portion 33m protrudes from the flange portion 311m along the longitudinal direction of the developing cartridge 10m in a direction away from the first side wall 11m. Additionally, the flange portion 311m also has the notched portion 312m. When the transmission member 4m falls into the notched portion 312m, the cam member 3m interrupts the transmission of force to the transmission member 4m.

The transmission member 4m is in the form of a rod, one end of which is positioned against the flange portion 311m of the cam member 3m allowing it to be driven by the cam portion 33m, and the other end of which is connected to the detected member 6m allowing it to drive the detected member 6m to move.

The detected member 6m is supported at the second end of the covering portion in a manner allowing it to pivot in the up-down direction. Specifically, the force receiving portion 61m of the detected member 6m extends upwardly and is inserted into an opening or groove at the second end of the transmission member 4m allowing it to drive the detected member 6m when the transmission member 4m moves left or right.

The connection portion 62m of the detected member 6m is pivotally attached to the covering portion, and the pivot axis of the connection portion 62m is located below the force receiving portion 61m, and the detected portion 63m is located below the force receiving portion 61m and below the transmission mechanism 200m of the detection unit when mounted in the imaging apparatus, and the detected portion 63m can trigger the transmission mechanism 200m when it pivots up and down.

In this embodiment, when the developing cartridge 10m is mounted in the imaging apparatus, the detected portion 63m of the detected member 6m is pressed against the transmission mechanism 200m. As a result, the force receiving portion 61m of the detected member 6m pushes the transmission member 4m towards the right side causing the transmission member 4m to be firmly pressed against the cam member 3m.

The coordination of the various components during the process of the developing cartridge being detected by the imaging apparatus will now be described with reference to FIGS. 38a through 38c.

As shown in FIG. 38a, when the developing cartridge 10m is mounted in the imaging apparatus, the detected portion 63m of the detected member 6m is pressed by the transmission mechanism 200m, and the transmission member 4m is pressed against the flange portion 311m of the cam member 3m.

As shown in FIG. 38b, when the cam portion 33m of the cam member 3m pushes the force receiving portion 41m of the transmission member 4m, the transmission member 4m

moves towards the left side of the developing cartridge 10m, which in turn pivots the force receiving portion 61m of the detected member 6m. Consequently, the detected portion 63m of the detected member 6m moves upwardly pushing against the rotation of the transmission mechanism 200m of the detection unit enabling detection.

As shown in FIG. 38c, when the force receiving portion 41m of the transmission member 4m moves from the top of the cam portion 33m towards the root, the detected member 6m drives the transmission member 4m towards the right side of the developing cartridge 10m under the action of the pressing force of the transmission mechanism 200m.

When the force receiving portion 41m of the transmission member 4m moves to the notched portion 312m, under the action of the pressing force of the transmission mechanism 200m, the force receiving portion 41m of the transmission member 4m falls into the notched portion 312m, pushed by the detected member 6m. It then moves to the right side of the developing cartridge 10m under the action of the force from the transmission mechanism 200m. The cam member 3m continues to rotate but the force receiving portion 41m is no longer driven by the cam portion 33m. As a result, the transmission of force is interrupted.

This structure of the developing cartridge results in a simple clutch mechanism and low manufacturing cost.

Embodiment 12

This embodiment is an improvement based on the preceding embodiments and their variations. The shape and structure of the developing cartridge 10k in Embodiment 12 are essentially the same as the developing cartridges in the preceding embodiments, and the same parts will not be repeated, and the following mainly describes the differences.

As shown in FIGS. 39 to 41, the developing cartridge 10k in the present embodiment is further provided with a chip 91 and a chip mounting bracket 92 for mounting the chip 91. The chip mounting bracket 92 is configured to be mounted to the cartridge body 1k. Specifically, the chip 91 and the chip mounting bracket 92 are provided at the first end (also the drive end) of the developing cartridge 10k, positioned farther from the development roller 14k than the coupling member 21k.

In some embodiments, the developing cartridge 10k may be removably mounted to a drum cartridge having a photoconductive drum. In this configuration, the developing cartridge 10k would be mounted together with the drum cartridge into the imaging apparatus. The drum cartridge may further comprise a pressure applying member, a locking member, and a separation member. The pressure applying member is configured to apply a force to the developing cartridge 10k mounted in the drum cartridge causing the development roller 14k and the photoconductor drum to come in contact with or close proximity to each other for performing developing operations. The locking member is used for locking and releasing the developing cartridge 10k when mounted in the drum cartridge. Specifically, the locking member is a rotatable component including a locking portion and a pushing portion. The separating member is configured to receive a force from the separating mechanism of the imaging apparatus and push the developing cartridge 10k causing the development roller 14k to move away from the photoconductor drum when an imaging operation is not being carried out. This results in the development roller 14k separating from the photoconductor drum.

The developing cartridge 10k has a locked portion 96, a forcing portion 97, a pushed portion 109, and a separation

force receiving portion 98 on the second side wall 12k of the cartridge body 1k. The locked portion 96 protrudes from the rear side of the second side wall 12k and is designed to be snap-fit with the locking member on the drum cartridge 5 when the developing cartridge 10k is mounted in the drum cartridge. The forcing portion 97 is configured to receive a force from the pressure applying member causing the development roller 14k and the photoconductor drum to contact or come close to each other. Specifically the forcing portion 97 10 is provided at and protrudes from the rear side of the cartridge body 1k, and the forcing portion 97 is provided in a more rearward position than the locked portion 96. The separation force receiving portion 98 protrudes from the second side wall 12k and is designed to receive the action 15 force from the separation member. This causes the developing cartridge 10k to move in a direction away from the photoconductor drum, thereby achieving separation between the photoconductor drum and the development roller 14k. The separation force receiving portion 98 is located nearer 20 to the development roller 14k than the locked portion 96. The pushed portion 109 receives an action force from the pushing portion of the locking member causing the developing cartridge to pivot, thereby causing the locked portion 96 to disengage from the locking portion. Specifically, the 25 pushing portion pushes the pushed portion 109 from its lower side. The pushed portion 109 is positioned between the locked portion 96 and the separating force receiving portion 98.

When projected along the longitudinal direction of the 30 developing cartridge 10k, the separation force receiving portion 98 is located at on or near the line connecting the center of rotation of the development roller 14k to the rotational axis of the coupling member 21k. The separation force receiving portion 98 is disposed nearer to the development roller 14k than the locked portion 96 and the forcing portion 97. Specifically, the separation force receiving portion 98 protrudes from the second side wall 12k along the longitudinal direction of the developing cartridge 10k passing through a through-hole located in the bearing member 40 100. This bearing member 100 is mounted on the second side wall 12k of the cartridge body 1k.

A sealing assembly is also provided between the cartridge body 1k of the developing cartridge 10k and the development roller 14k, the powder feed roller, and the powder 45 discharge knife 15k to prevent toner from leaking through the gaps between these components. Specifically, in this embodiment, the sealing assembly comprises a first sealing member 93, a second sealing member 94, and a third sealing member 95. The first sealing member 93 is provided at the 50 two ends of the longitudinal direction of the opening portion of the cartridge body 1k to seal the gap between the development roller 14k and the cartridge body 1k. Specifically, the first sealing member 93 may be made of felt.

The second sealing member 94 is in the form of an 55 elongated strip provided between the powder discharge knife 15k and the cartridge body 1k. It is positioned on the rear side of the opening portion 100k to seal the gap between the powder discharge knife 15k and the cartridge body 1k. The second sealing member 94 may be made of sponge. The 60 third sealing member 95 is provided between the development roller 14k and the cartridge body 1k. It is positioned on the front side of the opening portion 100 to seal the gap between the development roller 14k and the rear side of the opening portion. The third sealing member 95 may be in the 65 form of a resilient wiper or sheet.

The joints between the first sealing member 93 and the second sealing member 94 and between the first sealing

member 93 and the third sealing member 95 may be created through an interference fit or filled with glue. The first sealing member 93, the second sealing member 94, and the third sealing member 95 are connected to form an annular sealing body. This sealing body surrounds the opening portion 100k.

The powder compartment of the developing cartridge is also provided with a stirring member. This stirring member comprises a shaft portion 107k and a stirring portion 108k extending outwardly from the shaft portion 107k. Additionally, a concave portion 106k is provided at the top of the powder compartment. The concave portion 106k allows to prevent the stirring portion 108k from interfering with the side wall of the powder compartment during rotation.

In some embodiments, a support member 99 is provided between the third sealing member 95 and the cartridge body 1k. This support member 99 is in the form of an elongated strip that supports the third sealing member 95, allowing it to be tilted at an angle.

In some embodiments, the separation force receiving portion 98 and the bearing member can be made electrically conductive. In this configuration, the separation force receiving portion 98 can receive electrical power from the imaging apparatus and pass it through the bearing member to components such as the development roller 14k.

Across various embodiments and their variations, the movement direction of the detected member can also be simply changed as required. Additionally, the position of the detected member can also be flexibly designed, greatly improving the flexibility of the design of the developing cartridge. Furthermore, by adjusting the position of the detected member, it facilitates the miniaturization of the developing cartridge.

Throughout the various embodiments and their variations, the detected member is driven by a transmission member, with at least a portion moving along the longitudinal direction of the cartridge body to drive the detected member. This design eliminates the rotary shaft of the stirring member, which not only eliminates the risk of the need for using the rotational shaft of the stirring member being prone to deformation or even fracture, but also solves the problem of delayed transmission of drive force due to deformation of the rotary shaft of the stirring member to transmit the driving force to the detected member. Consequently, this not only eliminates the risk of deformation or even breakage of the rotational shaft of the stirring member, but also solves the problem of delayed transmission of the drive force due to deformation of the rotational shaft of the stirring member, and improves the detection accuracy.

Finally, it should be noted that, unless there are contradictory or mutually exclusive circumstances, the different embodiments and their variations disclosed above may be cited, referred to, or combined with each other. Additionally, the technical features of different embodiments and their variations may also be combined and/or replaced with each other.

The aforementioned embodiments are provided to exemplify the technical solution of the present disclosure and are not intended to be limiting thereof. To facilitate the differentiation of different components, the present disclosure introduces terms such as "first", "second", etc. However, the terms "first", "second", etc. are not to be understood as quantitative limitations on these components. For example, when the driving member described in the present disclosure is described as having a second gear portion, it should not be interpreted to mean that the driving member necessarily has a first gear portion or a third gear portion.

According to the description provided, the parts described as "first", "second", and the like may be singular or may include a plurality of parts. The terms "upper", "upper side", "lower", and "lower side" are based on the illustrations in the accompanying drawings and are not intended as specific limitations on their orientation. Although the present disclosure has been described in detail with reference to the foregoing embodiments, a person of ordinary skill in the art should understand that it is still possible to modify the technical solutions described in the foregoing embodiments or to replace some or all of the technical features therein with equivalent ones. Such modifications or replacements should not be considered to alter the essence of the corresponding technical solutions or extend beyond the scope of the technical solutions of the embodiments described in the present disclosure.

What is claimed is:

1. A developing cartridge removably mountable in a main assembly of an imaging apparatus along a front-rear direction of the developing cartridge, comprising:

a cartridge body;

a drive force receiving unit, provided at a first end of the developing cartridge;

a driving member, provided at the first end of the developing cartridge and configured to receive a drive force and move;

a transmission member configured to receive a force from the driving member, wherein the force from the driving member causes at least a portion of the transmission member to move in a longitudinal direction of the cartridge body;

a detected member, provided at a second end of the developing cartridge opposite to the first end along the longitudinal direction of the cartridge body, the detected member being configured to be driven by the transmission member; and

a sliding groove portion provided on an upper surface of the cartridge body, wherein the transmission member is at least partially mounted in the sliding groove portion, and the sliding groove portion is configured to restrict movement of the transmission member along an up-down direction perpendicular to the longitudinal direction and a front-rear direction of the cartridge body.

2. The developing cartridge according to claim 1, wherein the sliding groove portion protrudes from the upper surface of the cartridge body, and the sliding groove portion is positioned higher than the transmission member along the up-down direction.

3. The developing cartridge according to claim 1, wherein a plurality of sliding groove portions are provided and are spaced apart along the longitudinal direction of the cartridge body.

4. The developing cartridge according to claim 1, wherein the detected member is configured as a sliding member and is configured to slide in response to a pushing force from the transmission member.

5. The developing cartridge according to claim 4, wherein the detected member is configured to move linearly in the front-rear direction of the cartridge body.

6. The developing cartridge according to claim 1, wherein the transmission member comprises a rod portion slidably disposed on the cartridge body and extending along the longitudinal direction, and at least a portion of the rod portion is disposed between the first end and the second end of the developing cartridge.

7. The developing cartridge according to claim 6, wherein the detected member comprises a force receiving portion

39

and a detected portion, the force receiving portion being movably connected to the rod portion, and the detected portion extending in a direction different from an extension direction of the force receiving portion.

8. The developing cartridge according to claim 6, further comprising a resilient member provided at a first end of the rod portion and configured to support the rod portion. 5

9. The developing cartridge according to claim 1, wherein the driving member comprises a cam member, the cam member comprises a main body portion and a cam portion configured to push the transmission member, and the cam portion protrudes from an end face of the main body portion along the longitudinal direction of the cartridge body. 10

10. The developing cartridge according to claim 9, further comprising a clutch mechanism configured to interrupt transmission of the drive force to the transmission member, wherein the clutch mechanism comprises a missing tooth portion provided on an outer circumferential surface of the main body portion. 15

11. The developing cartridge according to claim 9, further comprising a clutch mechanism configured to interrupt transmission of the drive force to the transmission member, wherein the clutch mechanism comprises a notched portion provided on a radially outer side of the main body portion. 20

12. The developing cartridge according to claim 11, wherein the transmission member comprises a force receiving portion configured to be pushed by the cam portion, and the force receiving portion is configured to fall into the notched portion such that the force receiving portion no longer receives a force from the cam portion. 25

13. The developing cartridge according to claim 9, wherein the transmission member is movable between a first position not pushed by the cam portion and a second position pushed by the cam portion.

14. The developing cartridge according to claim 13, further comprising a resilient member configured to apply a force to the transmission member to enable the transmission member to move from the second position towards the first position. 35

15. The developing cartridge according to claim 1, further comprising a resilient member, wherein one end of the resilient member resists the cartridge body and another end of the resilient member resists the transmission member, and the transmission member comprises a housing portion for housing the resilient member. 40

16. A developing cartridge removably mountable in a main assembly of an imaging apparatus along a front-rear direction of the developing cartridge, comprising:

a cartridge body;

40

a drive force receiving unit, provided at a first end of the developing cartridge;

a driving member, provided at the first end of the developing cartridge and configured to receive a drive force and move;

a transmission member configured to receive a force from the driving member, wherein the force from the driving member causes at least a portion of the transmission member to move in a longitudinal direction of the cartridge body;

a detected member, provided at a second end of the developing cartridge opposite to the first end along the longitudinal direction of the cartridge body, the detected member being configured to be driven by the transmission member; and

a sliding groove portion provided on an upper side of the cartridge body, wherein the transmission member is at least partially and slidably accommodated in the sliding groove portion, and an upper surface of the transmission member is flush with or lower than an upper surface of the cartridge body.

17. The developing cartridge according to claim 16, further comprising a covering portion at least partially covering the transmission member.

18. The developing cartridge according to claim 17, wherein opposite ends of the covering portion are provided with a first exposed portion and a second exposed portion, respectively, the first exposed portion and the second exposed portion are configured as openings;

one end of the transmission member is configured to extend through the first exposed portion; and
a detected portion of the detected member is configured to be exposed through the second exposed portion.

19. The developing cartridge according to claim 17, wherein a second end of the covering portion is provided with an accommodating cavity for accommodating the detected member.

20. The developing cartridge according to claim 16, wherein the transmission member is a flexible transmission member, and the driving member and the flexible transmission member form a transmission direction-change unit configured to transmit a rotational force of the drive force receiving unit to the detected member to cause the detected member to move, a movement direction of the detected member intersects with a rotational axis of the drive force receiving unit, and the movement of the detected member is a linear motion, a rotational motion, or a curvilinear motion. 45
